FACE SHIELD FOR SAFETY HELMETS

Ted Zbikowski, 21220 W. Eight Mile Road,
Detroit, Mich.

Filed Nov. 16, 1960, Ser. No. 62,861

Term of patent 14 years

(Cl. D83—1)

FIG. 1 is a left side elevational view of a face shield for safety helmets embodying my new design, the right side being substantially the same, and the safety helmet being shown in broken lines for illustrative purposes only.

FIG. 2 is a front elevational view thereof.

FIG. 3 is a top plan view thereof.

I claim:

The ornamental design for a face shield for safety helmets, as shown and described.
